UNITED STATES PATENT OFFICE.

WILSON L. McLAUGHLIN, OF DES MOINES, IOWA.

DRYING APPARATUS.

Application filed June 27, 1927. Serial No. 201,834.

My invention relates to a novel method of economically removing excessive moisture from comminuted fuel or similar granular material.

5 One of the objects of my invention is to successfully dry comminuted fuel such as pulverized coal, peat, sludge, culm, and the like without destroying valuable volatile matter in the same by harmful oxidizing 10 gases.

A still further object of my invention is to provide a drier for removing moisture from granular matter which at all times is completely under the control of the operator, whereby any desired dryness of the matter may be obtained.

15 A still further object of my invention is to provide a novel drier for removing uncombined water from pulverized material 20 that will uniformly dry all material that passes from the same.

A further object of my invention is to provide for drying material reduced to impalpability without loss of the material.

25 A still further object is to provide a material drier which is capable of inspection while the material is being dried.

More specifically, the object of this invention is to deposit the material to be dried 30 upon a rotatably mounted heated platform above which is a series of adjustable plows for stirring and removing the material thereon.

These and other objects will be apparent 35 to those skilled in the art.

My invention consists in the construction, arrangement and combination of the various parts of the device, whereby the objects contemplated are attained as hereinafter more 40 fully set forth, pointed out in my claims and illustrated in the accompanying drawings, in which:

Fig. 1 is a side sectional view of my complete device installed and in use.

45 Fig. 2 is a top plan sectional view of a heat distributing container beneath the rotatable drier and is taken on line 2-2 of Fig. 1.

Fig. 3 is a top plan sectional view taken 50 on line 3-3 of Fig. 1 and shows a rotary platform drier and a series of plows in operative position above the same.

The laboratory experiences and practices have proven that fuel is consumed with the highest efficiency when reduced to powder 55 and combined with the proper proportions of air. To secure efficient and complete pul-

verization, it is necessary that substantially all uncombined water shall be removed from the same. Also in burning fuel of this nature, it must be in a dry state. Although 60 my device may be used for the drying of many other types of material, it is especially to meet the need of drying coal and such carbonaceous substances.

There are several devices now on the 65 market for drying comminuted fuel such as the rotary tube drier and drying tower. In the rotary tube drier, there is no way of controlling the amount of moisture to be removed from the material. The chance 70 of removing certain physical characteristics of the fuel, is always present. There is no way of watching the drying process, and one must accept the material in an unknown state as it is discharged from the rotary tube 75 drier. In the drying tower, the comminuted fuel is dropped into the tower against a rising heated gas. This rising gas carries with it, much of the pulverized material and the same is wasted. This gas has an oxidizing 80 action that destroys many of the valuable properties of the fuel. These and other disadvantages have been overcome by my device as will hereinafter be appreciated by 85 those skilled in the art.

I have used the numeral 10 to designate the heat distributing and combustion chamber of the device having the inlet pipe 11 designed to expel products of combustion into the chamber. Inside the heat chamber 90 10 is a circular wall 12 as shown in Fig. 2, to cause the heat to come into contact with and be evenly distributed against the bottom of my rotatably mounted drying platform before the same passes from the chamber. 95 Secured to the bottom of the chamber, or container 10 by suitable means is the cone-shaped supporting member 13 having the ball bearing 14 mounted in its top portion. Resting upon the top of this ball bearing 100 is a bracket member 15 secured by suitable means to the underside of my platform drier 16, which has been heretofore referred to. Permanently secured to the drying platform 16 near its center and communicating with the inside of the heat distributing container 10, is the chimney 17. By this construction, if the chimney 17 is rotated, the drying platform 16 will be rotated above the heat distributing container. For preventing any side play of the chimney 17, I 105 have provided the bearing member 18 se-

cured to the landing 19 with the beams 20 interposed, as shown in Fig. 1. Permanent-
ly secured on this chimney above the land-
ing 19 is the large wheel 21 having sprocket
teeth 22 on its periphery. In order that
the weight of this large wheel will not rest
entirely upon the chimney 17, I have pro-
vided a series of supporting rollers 23, each
rotatably secured to a bearing member 24
secured to blocks 25, which rest on the land-
ing 19. The numeral 26 designates a stand
on the landing 19 and secured upon which is
an electric motor 27. Rotatably mounted in
the bearing members 28 secured to this stand
15 is the shaft 29 having one end in operative
engagement with the clutch 30, which is
shown in conventional form and which is
designed to be capable of operative engage-
ment with the motor 27. Permanently se-
cured on the opposite end of this shaft is a
bevel gear 31 in operative engagement with
a second bevel gear 32 permanently secured
to one end of the shaft 33. This shaft 33 is
journaled in the members 34, which are se-
cured to the stand 26. Permanently se-
cured to the other end of this shaft 33 is the
pinion 35 in operative engagement with the
teeth 22 of the wheel 21. From this con-
struction, it will readily be seen that if the
30 motor is running and the clutch 30 is in
operative engagement with the same, the
drying platform 16 will slowly be rotating.
Embracing the chimney 17 and terminat-
ing a short distance above the platform 16
35 is a feeder pipe 36 having a funnel 37 in-
tegrally formed on its upper end. This
pipe is secured and held in proper position
by braces 38 leading from the downwardly
extending beams 39 secured to the landing
19. The numeral 40 designates a storage
bin mounted on the landing 19 having an
outlet pipe 41 leading to and capable of
discharging granular matter 42 such as
powdered coal into the funnel 37. This
45 granular matter passes down through the
pipe 36 around the pipe 17 and onto the
drying platform 16, as shown in Fig. 1. To
prevent arching or clogging of this matter
in the pipe 36, I have provided lugs 47 on
50 the rotating chimney 17. Having one of
their ends secured to the pipe 36 and their
other end secured to a flooring 54 are a plu-
rality of bracket members 48 radially ex-
tending over the drying platform 16. Ro-
tatably mounted in each of these bracket
55 members is a plurality of downwardly ex-
tending rods 49. Secured to the lower ends
of each of these rods is a small plow 50.
Secured to each of these rods 49 is a lateral-
60 ly extending arm 51. The numeral 52
designates a bar pivotally mounted on each
series of arms 51, as shown in Fig. 3. By
this construction, if the bar 52 is recipro-
cated, the plows which are in operative en-
gagement with that particular bar will be

rotated, thereby changing their angle rela-
tive to a given path. The movement of
each of these bars 52 is accomplished by the
ordinary and well known hand lever 53,
which may be locked in any desired posi- 70
tion.

The practical operation of the device is
as follows: Suitable fuel, mixed with the
proper proportions of air, is injected into
the chamber 10 through the pipe 11. This 75
inflammable matter is first ignited through
the small opening 43 in the side wall of the
chamber. After being ignited and success-
fully generated the heat from the same will
follow the circular wall 12 around to the 80
center of the distributing chamber during
which it will come in contact with the plat-
form 16 before it passes through the chim-
ney 17. The motor 27 is then started, which
will slowly rotate the chimney 17 and the 85
rotatably mounted drying platform 16. The
rotation of the chimney will cause the gran-
ular matter to be dried to pass out of the
distributing pipe 37 onto the drying plat-
form. As the plows 50 are held stationary 90
adjacent the top surface of the drying plat-
form, the slowly rotating platform will
bring the material to be dried in contact
with these plows, which, due to their con-
struction and position, will stir the material 95
and work the same outwardly toward the
marginal edge of the platform. These
plows should be so constructed and arranged
that at least one series of plows will catch
the oncoming granular material and turn it 100
over in a direction opposite from the other
plows. This assures the thorough stirring
of the material on the hot drying platform.
If the material is very wet, the angle of
the plows should be so set that they will not 105
readily force the material to the edge of the
platform. If the material is not very damp,
the plows should be so set that the same
will readily pass from the center of the plat-
form to the periphery of the platform. The 110
angle of the plows may be quickly changed
and permanently held in the desired position
by the hand levers 53. One of the series of
plows should be adjacent the receiving pipe
55, as shown in Figs. 1 and 3, so that the 115
last plow in this series will catch the ma-
terial that is worked to the edge of the plat-
form and force it into the pipe 55, as illus-
trated in Fig. 1. To aid in guiding the
material that has reached the periphery of 120
the platform to pass from the platform 16
to the pipe 55, I have provided the projec-
tion 56 extending a short distance over the
marginal edge of the rotatably mounted
platform. The pipe 55 may lead and de- 125
posit the dried material at any desired place.

From the foregoing description, it will
readily be seen by those skilled in the art,
that I have provided a drying apparatus
that will remove moisture from granular 130

matter without harming the same and which is always under complete control and inspection by the operator.

Some changes may be made in the construction and arrangement of my improved drying apparatus without departing from the real spirit and purpose of my invention and it is my intention to cover by my claims any modified forms of structure or use of 10 mechanical equivalents which may be reasonably included within their scope.

I claim:

1. In a device of the class described, a heat distributing chamber, a rotatably mounted platform inclosing the top of said chamber, a chimney secured to the center of said platform and communicating with said heat chamber, a distributing pipe embracing said chimney, a means for rotating 20 said chimney and terminating above the said platform, a pipe for supplying granular material to be dried to said distributing pipe, and a stirring means for agitating the material on said platform.

2. In a device of the class described, a heat distributing chamber, a platform rotatably mounted above said heat chamber, a chimney permanently secured to said platform near its center and communicating with 25 said chamber, a means for rotating said chimney, a material distributing pipe em-

bracing said chimney and terminating above said platform, a pipe for feeding the material to be dried to said distributing pipe, lugs on said chimney and inside said distributing pipe, and a means for agitating and removing said material from said platform.

3. In a device of the class described, a heat chamber, a rotatably mounted flat platform inclosing the top of said heat chamber, a pipe for supplying material to be dried to the center of said platform, a peripheral flange integrally formed on said platform, a series of plows for stirring and removing 45 said material, and a raised portion integrally formed on said platform and directly under said pipe for guiding and promoting the passing of said material into said plows.

4. In a device of the class described, a heat chamber, a rotatably mounted platform above said chamber, a chimney secured to the center of said platform and communicating with said heat chamber, a means for 50 rotataing said chimney, and a distributing pipe embracing said chimney and terminating above said platform for supplying granular material to be dried to said platform.

WILSON L. McLAUGHLIN.
